Primary Examiner—Cathron C. Brooks*Assistant Examiner*—Austin Murphy(74) *Attorney, Agent, or Firm*—Wolf, Block, Schorr & Solis-Cohen LLP(57) **CLAIM**

The ornamental design for a modulator, as shown and described.

DESCRIPTION

FIG. 1 is a perspective view of a modulator showing my design.

FIG. 2 is a right-side view of the modulator of FIG. 1.

FIG. 3 is a left-side view of the modulator of FIG. 1.

FIG. 4 is a front view of the modulator of FIG. 1.

FIG. 5 is a rear view of the modulator of FIG. 1.

FIG. 6 is a top view of the modulator of FIG. 1.

FIG. 7 is a bottom view of the modulator of FIG. 1.

FIG. 8 is an articulated view of the right-side of the modulator of FIG. 1.

FIG. 9 is another articulated view of the right-side of the modulator of FIG. 1.

FIG. 10 is another articulated view of the right-side of the modulator of FIG. 1.

FIG. 11 is another articulated view of the right-side of the modulator of FIG. 1.

FIG. 12 is another articulated view of the right-side of the modulator of FIG. 1; and,

FIG. 13 is another articulated view of the right-side of the modulator of FIG. 1.

The broken lines shown in the drawings form no part of the claimed design.
